UNITED STATES PATENT OFFICE.

HENRY J. BABCOCK, OF NORTH TONAWANDA, NEW YORK, ASSIGNOR TO AMERICAN DISTRICT STEAM COMPANY, OF NORTH TONAWANDA, NEW YORK, A CORPORATION OF NEW YORK.

APPARATUS FOR CENTRAL-HEATING-PLANT SYSTEMS.

1,368,013.

Specification of Letters Patent.

Patented Feb. 8, 1921.

Application filed December 7, 1918. Serial No. 265,779.

To all whom it may concern:

Be it known that I, HENRY J. BABCOCK, a citizen of the United States of America, residing at North Tonawanda, in the county of Niagara and State of New York, have invented certain new and useful Improvements in Apparatus for Central-Heating-Plant Systems, of which the following is a specification, reference being had therein to the accompanying drawing.

This invention relates primarily to central heating plant systems, and has more especial reference to structures for guiding and properly alining certain shiftable instrumentalities thereof in relation to a portion of an expansion joint or the like, and contemplates a novel form of guide or sleeve for use in connection therewith.

While its application is unrestricted, it is particularly successful and useful when employed for guiding feed-pipes or mains in relation to an expansion-joint in steam heating systems and the like.

It has been found in practice that a pipe-line will sag or warp more or less, and the creeping or movement of this line—due to expansion and contraction—will cause the pipe to push unevenly into the expansion-joint-slip instead of in a truly concentric manner. This angularity or unevenness of thrust causes a compression on the packing at one side of the joint and leaves an opening or clearance between the slip and packing on the other side of the joint and quickly wears out the packing. This permits leakage of steam (or other heating medium) between the packing and the slip.

It is contemplated as an object of the present invention to guide and aline the pipe or main with relation to the expansion-joint so that it will enter the stuffing-box thereof in a true and concentric manner: Thereby sagging and warping will be prevented, and the difficulties above enumerated will be avoided.

A further object within the contemplation of the invention is to produce an alining or guiding sleeve of such construction that it may be readily applied and removed from a pipe, main, or the like, and be placed at a distance from the expansion-joint as distinguished from devices of the prior practice and constituted as a part of the expansion-joint itself; the structure being such that it

may be embedded during the construction of the conduit and as a part thereof so that it will properly aline and guide the pipe and, thus, prevent sagging thereof, and, at the same time, permit any necessary longitudinal movement of the pipe due to expansion and contraction thereof.

Other objects and advantages will, in part be apparent and in part be brought out in the following description.

In the accompanying drawings I have illustrated a preferred embodiment of the invention; but it is to be understood that I intend this disclosure as merely illustrative and that the structure, thus revealed, is susceptible of a wide range of modification and variation without departing from its spirit or sacrificing any of its salient features or underlying principles.

In these drawings:

Figure 1 is a diagrammatic view in vertical longitudinal section, showing an application of the present invention to a main or pipe line of a heating system;

Fig. 2 is a view in side elevation of the alinement guide constituting a component of the structure;

Fig. 3 is a view in transverse section on the line 3—3, Fig. 2;

Fig. 4 is a view in side elevation of a slightly modified form of alinement guide;

Fig. 5 is a fragmentary view, similar to Fig. 1, on an enlarged scale;

Fig. 6 is a detail view in longitudinal section of the saddle-member; and

Fig. 7 is a view in transverse section of the same.

Referring specifically to the drawings, the reference-numeral 1 designates, generally, a steam-conduit of the type now in extensive use in city steam-heating systems. It comprises alined pipe 2 connected by a joint 3 with a slip 4 which enters the stuffing-box (not shown) of an expansion-device 5, the latter usually being mounted in a man-hole 6 or the like. The pipes are surrounded by a pipe-covering 7 and by a wooden casing 8 in spaced relation to the pipe-covering, the latter being embedded in concrete 9 or the like which is extended to form a base for the expansion-device 5.

To obviate the aforementioned tendency in these systems, as usually installed, of the pipes to sag or warp and thereby cause an

uneven entry of the slip 4 within the expansion-device and the consequent uneven wearing away of the packing in and leakage from the stuffing-box, there is provided, in 5 spaced relation to the expansion-device, an alinement-guide or sleeve 10. One of these is usually placed around the pipe at a short distance from the point where the slip enters the expansion-device, and another is usually 10 disposed along the pipe at a distance from the first alinement guide. Between the alinement-guide and the joint there may also be provided a saddle-member 11, the arrangement being such that the alinement- 15 guides and the saddle constitute a means of alining the pipe and guiding the slip within the packing joint concentrically thereof so that uneven wear upon the packing is obviated. The saddle-member is generally placed at the point where the pipe 20 leaves the main to enter the manhole. As seen in Fig. 1, the alinement guide is arranged around the pipe, sufficient space between the pipe and the guide being allowed 25 to permit the pipe freely to move longitudinally therein. The guide is embedded in the concrete or otherwise suitably fixed in relation to the pipe.

The alinement-guide itself is preferably 30 made in sections. In Figs. 2, 3 and 4, it is shown as comprising two spaced-apart end-sections or disks 12 and 13 having at their adjoining edges flanged portions 14 adapted to be suitably secured together, as by bolts 35 15. Centrally of each of these disk-members is a collar or sleeve 16 hollowed out so that when joined together a space 17 will be provided for the pipe or the like. Each section has, in addition to the spaced-apart end- 40 flanges, a bracing member or web 18. In cross-section, as shown in Fig. 3, when the members are secured together, the members 12 and 13 have the appearance of disks. The bracing-members 18 and flanges 14 are 45 arranged in angular relation to the faces of the disks and the space between the disks and flanges constitutes a housing for a heat-insulating material 19, such as asbestos or the like. 50 In Fig. 4 there is shown a slightly modified form of structure, wherein there is provided but one central flange or disk 20. The webs 21 thereon (corresponding to the bracing-members 18 just described) are tapered 55 from a point centrally and converge toward their outer edges, meeting at the periphery of the disk. Joining flanges 22 are provided and these also may be tapered to correspond with the tapering of the bracing-members 21.

The saddle-member 11, as shown particularly in Figs. 6 and 7, comprises a plate 25 shaped to correspond approximately with the outer contour of the pipe covering or 60 main which is to be placed thereon. This

plate is mounted pivotally upon a base 23, and may have spurs 24 disposed in proximity to the pipe which it is to carry. The pivotal mounting of the plate upon the base permits it to accommodate itself to the various shifting positions of the pipe, and the ribs minimize friction between the pipe and the plate and also constitute a bracing means for the plate itself. 70

The provision of the alinement-sleeves 75 or guides, in a heating system of the type herein shown, insures a definite parallelism between the outer surface of the slip-joint and the inner surface of the expansion-device packing-joint. The provision of the 80 guides, as a separate and distinct entity from the expansion-joint itself, greatly facilitates the installation of these systems, simplifies the construction of the expansion joint itself, and (in addition to minimizing 85 leakage) adds materially to the life of the joint. The alinement-guide is so constructed that it may be readily attached to and detached from pipes already installed, and the construction is such that a solid anchorage 90 is provided for the guide.

From the foregoing, it will be apparent that the invention provides effective means for obviating the difficulties and for producing the advantages hereinabove set forth. 95 While it has been disclosed in the particular embodiment here illustrated and described, it will be understood that various changes in the construction and arrangement of the parts may be resorted to without departing 100 from the principles of the invention.

What I claim is:—

1. In combination with an expansion-member and a heat insulated pipe or the like associated therewith, means independent of 105 the expansion member and comprising a sleeve partially embedded in the insulation and loosely embracing the pipe for guiding the pipe and maintaining it in concentric arrangement with the expansion-member. 110

2. In combination with an expansion-member and a heat insulated pipe or the like associated therewith, means independent of the expansion-member and comprising a sleeve partially embedded in the insulation and loosely embracing the pipe for guiding the pipe and maintaining it in concentric arrangement with the expansion-member, and a saddle-member disposed between said guiding-means and expansion-member. 115

3. An alinement instrumentality comprising a collar adapted to loosely embrace a pipe, said collar including separable components; a flange associated with each component; securing means adapted to be disposed on the flanges; a disk member disposed on the collar and in angular relation thereto and adapted to be partially embedded in insulating material to anchor the 120 125 130

alinement instrumentality, and a bracing web associated with the disk and collar.

4. In combination with an expansion-member and a heat insulated pipe or the like 5 associated therewith; means independent of the expansion-member and comprising a sleeve embedded in the heat insulation for guiding the pipe and maintaining it in concentric arrangement with the expansion- 10 member; and a saddle-member disposed between said guiding-means and expansion-member.

5. In combination with an expansion-member and a heat insulated pipe or the like 15 associated therewith; means independent of the expansion-member and comprising a

sleeve embedded in the heat insulation for guiding the pipe and maintaining it in concentric arrangement with the expansion-member; a saddle-member disposed between 20 said guiding-means and expansion-member; said saddle-member comprising a base; a fulcrum thereon; an elongated plate mounted on said fulcrum; and spurs disposed between said plate and said pipe.

25

In testimony whereof I affix my signature in presence of two witnesses.

HENRY J. BABCOCK.
